UNITED STATES PATENT OFFICE.

FRANCIS EDWIN EDWARDS, OF CRYSTAL LAKE, ILLINOIS, ASSIGNOR TO STROMBERG
MOTOR DEVICES COMPANY, OF CHICAGO, ILLINOIS, A CORPORATION OF ILLINOIS.

FUEL-FEED SYSTEM FOR AUTOMOBILES AND THE LIKE.

Application filed November 30, 1917. Serial No. 204,484.

To all whom it may concern:

Be it known that I, FRANCIS EDWIN EDWARDS, a citizen of the United States, residing at Crystal Lake, in the county of McHenry and State of Illinois, have invented a certain new and useful Improvement in 5 Fuel-Feed Systems for Automobiles and the like, of which the following is a full, clear, concise, and exact description, reference being had to the accompanying drawings, forming a part of this specification.

My invention relates to fuel feed systems for automobiles and the like.

In present automobile practice it is customary to supply the gasoline from a main tank to the carbureter float chamber in one of three ways, namely, by gravity feed, by pressure feed, by suction feed.

Gravity feed can not generally be secured 20 because of the design of the modern automobile and the inability to find room for an elevated tank.

Pressure feed, as at present employed, has the serious disadvantage of the loss of pressure 25 when the tank is opened for filling and the difficulty of keeping the tank properly under pressure in normal running. There is also greater danger of leakage and serious loss of gasoline by a broken connection. An 30 other serious difficulty is the condensation of moisture from air forced into the tank. This accumulates until it freezes up the pipe line.

Suction feed has been widely adopted as 35 it obviates most of the difficulties of the pressure feed, but, as heretofore employed, it has disadvantages of its own. When the suction for operating the system is taken off of the manifold, the consequence is that carburation 40 is, to some extent, interfered with. The carbureter cannot be finely adjusted because of the varying conditions brought about by the suction feed system.

Sometimes the sticking of the parts causes 45 raw oil to be drawn into the manifold.

The most serious difficulty is the failure of 50 manifold suction systems to operate under conditions of wide open throttle. This is because at wide open throttle the suction in the manifold is so low as to be incapable of 55 operating the fuel feed system. The same, and other, difficulties of even more serious nature are encountered if the system is operated from the combustion space of the engine itself.

It is the aim of my invention to provide a feed system having the general capabilities of a suction feed system in that it can raise the fuel from a lower level to the carbureter without the disadvantages attendant upon such systems heretofore employed.

According to my invention, I provide a separate plunger connected to the operating parts of the engine. This plunger moves in a relatively stationary cylinder, although the 60 relation of these parts may be reversed. The cylinder is directly connected with a pumping chamber. This chamber contains a float that controls a valve, governing the application of the impulses of the piston to the 65 liquid to move the liquid from the lower level to the higher level. The piston and cylinder do not comprise a complete pump, as no valves are provided for the cylinder and the pipe between the pump and the 70 chamber conveys the pulsations of alternate compression and rarefaction of the air which fills said pipe and cylinder. The float controls the valves so that the proper amount of 75 fuel is delivered to the carbureter as is required by the demand of the engine. Thus, in theory, my invention presents a pump having an elastic plunger, the stroke of which is governed in accordance with the 80 demands of the carbureter by means of a 85 float.

I find this construction to be highly advantageous as it is reliable, economical and inexpensive. I do not intend to be limited to the precise constructions which I disclose 90 herein, as it is apparent that the embodiment of the invention may be widely varied.

In the accompanying drawings:

Figure 1 is a diagrammatic layout of the 95 system showing the cylinder and piston, and operating parts in section;

Figure 2 is an axial cross section of the valve chamber and

Figure 3 is a similar view of a modification.

The carbureter 1 supplies the proper mixture to the engine (not shown), fuel being supplied from the float chamber 2, which float chamber is replenished as liquid fuel is used from the main tank 3. The mechanism for replenishing the immediate supply of fuel in the float chamber 2, comprises the pulsating pump 4 and the pumping chamber 5.

The float chamber 2 employs a suitable 110

float controlled valve shown in dotted lines in Figure 1 for controlling the feed of fuel from the chamber 5.

The pulsating pump 4 comprises a cylinder 6, rigidly bolted by means of a bracket 7 to a frame member 8, preferably a part of the engine casing. The top of the cylinder is closed off by a cylinder head 9 which is threaded over the open end of the cylinder. 10 Within the cylinder 6 a reciprocable piston 10 is closely fitted. This piston is connected by means of a connecting rod 11, to an eccentric 12 on the shaft 13. The shaft 13 is preferably one of the shafts of the engine, 15 in this case the cam shaft of the engine for operating the valves. The eccentric 12 is connected to this shaft by means of a key 14.

It is to be understood that the construction of the pump 4 may be widely varied, the 20 particular feature being that this is not a complete pump, that is, it does not comprise inlet and outlet valves, but comprises only a generator of oscillations in pressure of the air within the cylinder. These alternate 25 compressions and rarefactions of the air in the cylinder are transmitted by means of a pipe 15 to the interior of the pumping chamber 5. The cylinder 6 and the pipe 15 contain air and it will be readily understood 30 that when the piston 10 moves downward the pressure of the air in the cylinder and pipe 15, and in the top of the pumping chamber 5, falls below normal atmospheric pressure creating a suction stroke in the 35 pumping chamber 5.

The pumping chamber 5 is connected by means of a pipe 16 with the main supply tank 3 on the inlet side of the pumping chamber. On the outlet side of the chamber 40 a pipe 17 connects the chamber with the float chamber 2. It is to be understood that the float chamber 2 is provided with the usual float controlled valve, as is well understood by those skilled in the art.

45 The pumping chamber 5, as shown in Figure 1, is provided with a mounting bracket 18 by means of which it is connected under the hexagon nut 19 on top of the float chamber 2.

50 The pumping chamber 5 comprises an outer cylindrical shell 20, the upper end of which is closed off by a cap 21. The elbow 22 communicates through a hole in the cap 21 with the interior of the pumping chamber and is connected to the pipe 15, which leads to the oscillation pump. The cap 21 is preferably secured to the open end of the shell 20 by means of screw threads and a flange, as is indicated in the drawings.

60 The bottom of the shell 20 is closed off by a screw plug 23 which has an interior flange 24 with apertures therethrough and a screen 25 over the same. The flange of the plug 23 extends upward against a partition 26 which 65 divides the interior of the casing 20 into two

compartments, namely, the main float compartment 27 and the inlet valve compartment 28. The inlet compartment 28 communicates by way of the opening 29 with the union 30 which forms the end of the gasoline supply pipe 16 shown in Figure 1. The main float compartment 27 is provided with an outlet passage 31 formed in a boss in the side of the wall 20, this boss being suitably machined to provide a valve port 32 for the outlet check valve 33. A screw plug 34 closes the top of the cage for the valve 33. Upon the outlet side of the valve 33 the port 35 communicates with the discharge pipe 17, leading to the inlet of the float chamber 2. 70 75 80 85

The wall or partition 26 which divides the casing 20 into two compartments has a depressed central hub 37 into which there is set the valve cage 38, this cage being held in place by the hollow screw plug 39 which is threaded into the interior of the cage. The plug 39 forms a valve passage 40 and the upper end of the plug forms a seat for the inlet check valve 41. The cage 38 has the ports 42 for permitting liquid fuel which enters past the valve 41 to pass into the float chamber compartment 27. The upper end of the cage 38 is bored to receive the controlling stem 43 which stem is governed by the float member 44 through which this stem 90 passes axially. The cap member 21, which closes the casing 20, is provided with an axial guide 45 in which the upper end of the stem or rod 43 is guided. A suitable bracket member 46 secured to the bottom of the cap member 21 provides pivotal support for the weighted operating levers 47 which connect the float 44 with the stem 43. The inner end of these levers 47 play between the collars 48, thereby causing the stem 43 to be 105 thrust downward when the float 44 rises. The stem 43 is of such a length that when the float is in its uppermost position, the lower end of the stem 43 engages the check valve 41 and presses it down upon its seat, closing 110 off the inlet port 40. The outlet check valve 33 is operable at all times but inasmuch as the outlet communicates with the float controlled valve in the float chamber 2, it is apparent that as soon as the float controlled 115 valve in the chamber 2 closes, the outlet check valve 33 will not be raised because of the incompressibility of the liquid fuel.

The operation of the system, thus far described, is as follows:

As soon as the engine is turned over, the shaft 13 is rotated, causing reciprocation of the piston 10 in the cylinder 6. The body of air contained in the cylinder 6, the pipe 15 and in the top of the pumping chamber 5 is alternately compressed and rarefied. The effect of these alternate compressions and rarefactions of the air in the pumping chamber 5 causes the inlet and outlet check valves 41-33, respectively, to close and open 120 125 130

alternately. Thus, during the first few strokes, air would be drawn from the pipe 16 until the liquid were drawn up into the pumping chamber 5. This air would be 5 driven out through the discharge port 35 and would pass up through the float chamber 2.

The alternate compressions and rarefactions of the air in the top of the pumping chamber 5 alternately draw in liquid fuel to 10 the inlet valve 41 and force the same out at the outlet check valve 33. This action continues until the float chamber 2 is closed off by the action of the float valve therein. Thereafter the compression impulses in the pumping 15 chamber 5 do not discharge any more gasoline from the pumping chamber 5 and the suction impulses only are effective. As the liquid is drawn into the float compartment 27 by the suction impulses the level of the 20 same rises until the float 44 operates upon the stem 43 to press the check valve 41 down upon its seat, closing off the further supply of liquid fuel. Thereafter, both compression and suction strokes are ineffective until the 25 level of the fuel in the float chamber 2 drops sufficiently to operate the float valve therein to permit more fuel to be pumped into the float chamber 2.

It will be seen at once that a system that 30 I have described is of the utmost simplicity and reliability; the power required to operate the impulse pump 4 is very slight. While I have shown the pumping chamber 5 as elevated above the float chamber 2, it is 35 not essential that this pumping chamber be thus elevated.

In Figure 3 I have illustrated a modified form of pumping chamber 5'. This chamber comprises the cylindrical side walls 50, the top of which is closed by a screw threaded cap 51, having a central hub 52 containing a valve port 53 and having valve seat 54 for the float controlled valve 55, which is mounted by means of the universal joint 56 on the float 57. The lower end of the casing 50 is provided with an enlargement 58 which forms a valve body for the check valve 59, this check valve governing the outlet port 60, which communicates by 40 way of the passages 61 and 62, with the bottom of the pumping chamber. The recess in which the check valve 59 operates is closed by a screw plug 63 which permits access to be had to said valve when necessary. The lower wall of the casing 50 is provided with a hollow projecting stud 65, surrounded by a cage or barrel 66, held in place by means of a screw plug 67. The cage 66 has an inlet nipple 68 which is 45 adapted to be connected to the pipe line 16 leading to the main tank 3. The cage may be turned so that the inlet nipple 68

faces in any desired direction. The interior of the cage 66 is provided with a screen 69 surrounding the stud 65. The bore 65 70 of the stud 65 communicates with the inlet nipple 68 through the radial openings 71. At its upper end the bore 70 merges into a valve port 72 controlled by the inlet check valve 73, which is held in a suitable 75 valve cage 74, this cage holding the check valve against displacement and also preventing the float 57 from interfering with the operation of the valve 73.

The port 53 in the top of the pumping 75 chamber 5' is adapted to communicate by way of the pipe 15 with the oscillation pump 4. The outlet port 60 is adapted to communicate with the carburetor float chamber 2 by way of the pipe 17. The inlet nipple 80 68 is adapted to communicate with the supply tank 3 by way of the pipe 16. The oscillations of pressure produced by the pump 4 are transmitted to the pumping chamber 5, and cause the valves 73 and 59 85 to operate to supply liquid fuel to the float chamber 2. The pump 4 is so proportioned that the suction impulse will produce sufficient lifting effect to raise the fuel from the main tank to the pumping chamber 5 or 5'. 90

When the float controlled valve in the float chamber 2 closes the discharge valve 59 becomes inoperative and the liquid fuel that is drawn into the pumping chamber 5 raises the float 57 and causes the valve 55 to close 95 against its seat 54, thus shutting off the effect of the oscillations in pressure upon the pumping chamber 5'. The universal joint 56 provides play between the valve 55 and the float 57. 100

I do not intend to be limited to the precise details of construction shown and described.

I claim:

1. In a fuel feed system, a pumping 105 chamber, a float in said chamber, projections holding said float spaced from the bottom of said chamber, one of said projections forming a housing, and an inlet valve covered by said housing. 110

2. In a fuel feed system, a pumping chamber, a conduit for delivering fluid impulses to said chamber, a tubular boss formed in the wall of said chamber to receive said conduit, a valve partly in said 115 boss adapted to close the end of said conduit, a float in said chamber supporting said valve, and stop means limiting downward movement of said float to prevent withdrawal of said valve from said boss. 120

In witness whereof I hereunto subscribe my name this 28th day of November, A. D. 1917.

FRANCIS EDWIN EDWARDS.
